JOSEPH T. FEWKES, OF PHILADELPHIA, PENNSYLVANIA, ASSIGNOR TO SENTRY SAFETY CONTROL CORPORATION, OF PHILADELPHIA, PENNSYLVANIA, A CORPORATION OF DELAWARE

DOWSER CONTROL MECHANISM FOR MOTION PICTURE PROJECTING MACHINES

Application filed June 4, 1928. Serial No. 282,844.

This invention relates to dowser control mechanism for motion picture projecting machines.

It is intended for use in an electric circuit in which there are placed in parallel a plurality of safety switches which operate to break the magnet circuit when the film of the projecting machine becomes broken or clogs, or when the motor fuse blows out, or when the 10 transmission belting of the motor breaks.

The control mechanism operates to drop the dowser into light obstructing position and to stop the motor which feeds the film in case any of the above mentioned difficulties arise.

Switches of the kind just mentioned are to a certain extent standardized today and their construction and method of operation are no doubt well known to those skilled in this art.

The object of the invention is to provide a 20 cheap, simple and efficient dowser control mechanism.

According to the invention the dowser control mechanism is mounted in a casing which has a shaft journaled therein and upon which 25 the dowser is fastened outside the casing, a magnet, a keeper, a pinion on the shaft, means connecting said keeper and meshing with said pinion for holding the dowser out of light obstructing position when the magnet 30 is energized, a film feeding motor switch in said casing, and means on said shaft for opening said switch when the magnet is deenergized and the dowser drops into light obstructing position.

The drawings illustrate an embodiment of 35 the invention and the views therein are as follows:—

Figure 1 is a vertical sectional view taken through the casing although a part of the 40 dowser is shown in full,

Figure 2 is a rear view of the mechanism with the cover removed and looking in the direction of the arrow A in Figure 1, and

Figure 3 is a cross-section of the complete 45 apparatus showing the dowser in a raised position and may be said to be taken on a line which is fairly indicated by 3—3 in Figure 1.

The dowser control mechanism is contained in a casing 11 which has an integrally formed 50 foot 12 for mounting the same upon a cone

of the lamp housing (not shown) of a motion picture projecting machine.

The method of attachment is shown to be by the screws which pass through holes 14 but it will be understood that while the cone 55 forms a suitable support for the apparatus, it is shown thereon merely as a convenient means of support and the particular foot illustrated may be eliminated and any form of mounting may be used.

The casing has a cover 16 which completely encloses the operating mechanism therein and this cover has a bearing 17 formed integrally therewith for the purpose of housing a shaft 18 which extends through said casing and through a bearing formed on the front wall 21 of said casing, and a dowser arm 22 is fixed to the end of the shaft by a set screw 23 which passes through the shank 24 and through said shaft.

The dowser arm extends below the shank 24 and is formed for supporting on each side thereof a plate 26, which plates are secured thereto and to each other by the rivets or other fastening means 27.

The front of the casing 11 is provided with an integrally formed stop 28 against which the dowser arm 22 is adapted to strike to limit the upward movement of the dowser.

The upper end of the dowser arm is provided with an operating handle 31 which is pivotally mounted at 32 and has an inwardly projecting latch 33 which is urged downward by the spring 34 fastened to the screw 36 in said arm.

The downward movement of the latch 33 is limited by the shape of the socket in which the handle is pivotally mounted.

The upper end of the casing is provided at its front with an inclined surface 37 beyond which is a notch 38 for receiving the latch 33 on the operating handle 31 and beyond this notch is a shoulder 39 for limiting the movement of the dowser arm.

Fitting within the casing and adjacent to the end wall 21 is a mounting plate 41 which is fastened thereto by screw 40 and upon which a magnet 42 is obliquely mounted by the bracket 43. Between the end wall 21 and 100

mounting plate 41 is a sheet of insulating material 45.

This magnet has a keeper 44 which is fastened to the long leg of a substantially J-shaped plate 46 and the other end of said plate is fastened by the screws 47 to the side face 48 of the gear segment 49. This gear segment meshes with a pinion 51 mounted on the shaft 18 and secured thereto by the pin 52. The gear segment 49 is rotatably mounted on a bolt 53 which extends through a positioning collar 54 and through the end wall of the casing where it is retained by means of the nut 56.

The shaft 18 is provided with insulating collars 57 and 58 between which is the finger 59 fastened to the shaft by the pin 61, and this finger is formed of insulating material and is adapted to engage a spring contact 62 fastened by its one end to the insulating mounting 60 by the screws 65 and nuts 63 and having on its other end a contact point 64 which engages the contact point 66 on the contact arm 67 which is secured by its one end to the insulating mounting 60 by the screw 65 and nuts 68. The screws 65 hold the insulating mounting in the casing.

The casing is provided with a standard approved cable clamp 69.

The nuts 63 and 68 form binding posts for fastening the switch into the motor circuit.

The operation of the dowser control mechanism is as follows:—

The motor for feeding the film mechanism is started by the operator when he presses downward on the operating handle 31 so as to disengage the latch 33 from the notch 38 and then turns the dowser arm slightly so that it will approach the position shown in Figure 3. The motor is started as soon as the shaft rotates sufficiently to disengage the finger 59 from the contact arm 62 to permit contact between the contact points 64 and 66. This starting of the motor is accomplished when the dowser is moved a short distance from its initial position and it is presumed that it will be running at full speed when the dowser is completely opened.

When any one of the safety switches which operate in the event of defective filming, as mentioned in the early part of this specification, breaks the circuit into which the magnet is connected by its wires 71 and 72, the magnet will be deenergized and will release its hold on the keeper 44 and the weight of the dowser will cause it to fall by gravity until it rests in a position such as shown in Figure 2 with its latch retained in the notch 38.

During the dropping of the dowser, the shaft 18 will rotate, thus rotating the pinion 51 which is meshed with the gear segment 49, and the finger 59 will be rotated so as to press the spring contact arm 62 outward to break the contact between the contact points 64 and 66. This will break the motor circuit.

It will be seen that when the magnet is energized, it will hold the keeper 44 firmly thereon and will prevent the rotation of the gear segment 49 and the finger 59 will thus be held out of contact with the contact arm 62 so as to prevent the breaking of the circuit formed by the contact points 64 and 66.

Of course, the control mechanism illustrated may be modified and changed in various ways without departing from the invention herein set forth and hereafter claimed.

The invention is hereby claimed as follows.

I claim:—

1. Dowser control mechanism comprising a casing, a shaft journaled in said casing, a dowser fixed on said shaft at right angles to the length of said shaft, a magnet, a keeper, and a gear segment on said keeper meshing with a gear on said shaft for holding said dowser out of light obstructing position when the said magnet is energized.

2. Dowser control mechanism comprising a casing, a shaft journaled in said casing, a dowser fixed on said shaft at right angles to the length of said shaft, a magnet, a keeper, a gear segment on said keeper meshing with a gear on said shaft for holding said dowser out of light obstructing position when the said magnet is energized, and means for opening the film feeding motor circuit when said magnet is de-energized.

3. Dowser control mechanism comprising a casing, a shaft journaled in said casing, a dowser fixed on said shaft at right angles to the length of said shaft, a magnet, a keeper, a pinion on said shaft, and a gear segment secured to the keeper and meshing with said pinion for holding said dowser out of light obstructing position when said magnet is energized.

4. Dowser control mechanism comprising a casing, a shaft journaled in said casing, a dowser fixed on said shaft at right angles to the length of said shaft, a magnet, a keeper, a pinion on said shaft, a gear segment secured to the keeper and meshing with said pinion for holding said dowser out of light obstructing position when the said magnet is energized, and means for opening the film feeding motor circuit when said magnet is de-energized.

5. Dowser control mechanism comprising a casing, a shaft journaled in said casing, a dowser fixed on said shaft at right angles to the length of said shaft, a magnet, a keeper, a pinion on said shaft, and a gear segment pivotally mounted and secured to said keeper, said gear segment meshing with said pinion and held against rotation by the influence of the magnet upon the keeper when said magnet is energized for holding said dowser out of light obstructing position.

6. Dowser control mechanism comprising a casing, a shaft journaled in said casing, a

dowser fixed on said shaft at right angles to the length of said shaft, a magnet, a keeper, a pinion on said shaft, a gear segment pivotally mounted and secured to said keeper, 5 said gear segment meshing with said pinion and held against rotation by the influence of the magnet upon the keeper when the said magnet is energized for holding said dowser out of light obstructing position, and means 10 carried by said shaft for opening the film feeding motor circuit when said magnet is de-energized.

In testimony whereof I have signed my name to this specification.

15 JOSEPH T. FEWKES.
